United States Patent Office

Des. 193,142
Patented July 3, 1962

193,142

TELEVISION ANTENNA

Robert Liftin, Bronxville, N.Y., and Alfred C. Denson, Rockville, Conn., assignors to Regent Electronic Development Co. Inc., New York, N.Y., a corporation of New York

Filed Oct. 25, 1961, Ser. No. 67,252

Term of patent 14 years

(Cl. D26—14)

FIGURE 1 is a view in perspective of a television antenna showing our new design.

FIGURE 2 is a rear elevational view.

FIGURE 3 is a top plan view.

FIGURE 4 is a bottom plan view.

FIGURE 5 is an end view as seen from the left of FIGURE 1.

We claim:

The ornamental design for a television antenna, substantially as shown.
